UNITED STATES PATENT OFFICE.

JOHN W. SMITH, OF CHICAGO, ILLINOIS, ASSIGNOR, BY MESNE ASSIGNMENTS, TO SANTO MANUFACTURING COMPANY, OF PHILADELPHIA, PENNSYLVANIA, A CORPORATION OF DELAWARE.

VACUUM-CLEANER.

1,128,630.

Specification of Letters Patent. Patented Feb. 16, 1915.

Original application filed May 29, 1908, Serial No. 435,633. Divided and this application filed December 8, 1908. Serial No. 466,476.

To all whom it may concern:

Be it known that I, JOHN W. SMITH, a citizen of the United States, residing in Chicago, in the county of Cook, State of Illinois, have invented a new and useful Vacuum-Cleaner, of which the following is a specification.

My present invention consists of a novel construction of a portable cleaning apparatus which is exceedingly compact and light in order that the same may be readily transported from one place to another.

In a copending application filed by me May 29, 1908, Serial No. 435,633, of which this is a division, I have described and broadly claimed a novel construction of a vacuum producing apparatus which is especially adapted to be employed in conjunction with vacuum cleaners.

It further consists of a novel construction of a vacuum cleaning apparatus wherein a dust separator is employed which is adapted to be connected with the cleaning devices, such as the nozzles, said separator communicating with a vacuum pump which is provided with connecting rods operatively connected with the follower head of the pumping apparatus and with a plurality of cranks on the motor shaft.

It further consists of a novel construction of a cleaning device having a vacuum compartment and a pressure compartment, the pressure compartment having located therein a suitable motor for actuating the vacuum producing mechanism, which latter is located intermediate of the vacuum compartment and the pressure compartment.

It further consists of a novel construction of a cleaning apparatus in which the motor is connected by means of suitable cranks with two connecting rods located on opposite sides thereof and preferably rigidly secured to the movable member of the vacuum producing device.

It further consists of a novel construction of a vacuum cleaner which may be employed for cleaning purposes in cases in which it is desirable to suck in the dirt and dust by connecting the hose to the inlet and which may also be employed for blowing the dirt and dust from the articles to be cleaned, in which case the hose is connected with the exhaust or outlet.

It further consists of other novel features of construction, all as will be herein-after fully set forth.

For the purpose of illustrating my invention I have shown in the accompanying drawings those embodiments thereof which are at present preferred by me, since the same have been found in practice to give efficient and reliable results, although it is to be understood that the various instrumentalities of which my invention consists can be variously arranged and organized and that my invention is not limited to the precise arrangement and organization of these instrumentalities as herein set forth.

Figure 1 represents a sectional elevation of a portable pneumatic cleaning apparatus embodying my invention. Fig. 2 represents a sectional elevation of Fig. 1. Fig. 3 represents a sectional elevation of another embodiment of my invention wherein the follower head of the vacuum producing apparatus is shown as a piston instead of a diaphragm.

Similar numerals of reference indicate corresponding parts in the figures.

Referring to the drawings:—1 designates a base provided with suitable rollers 2, whereby the same may be rolled along the floor when desired, although it is to be understood that my present device is so light that in practice the rollers may preferably be dispensed with and the device manually transported from place to place.

3 designates a casing which is secured to the base 1 by means of any suitable devices, said casing forming therein a pressure compartment 4, it being noted that as indicated in Fig. 1, the casing 3 is provided with a suitable exhaust or outlet 5, which is adapted to be connected with a hose or other suitable connection.

6 designates a motor of any desired or conventional type which is located in the vacuum compartment 4 and in practice I prefer to employ an electric motor which may be readily connected with a lamp circuit, and one object of my present invention is to devise a cleaning apparatus wherein a standard motor may be employed. The motor 6 is supported on the base 1 or secured thereto in any suitable manner and the motor shaft 7 is provided on opposite

sides thereof with the ball bearings 8 and on which latter are mounted the connecting rods 9.

10 designates fly wheels mounted on the 5 motor shaft 7. The connecting rods 9 are preferably rigidly connected by means of suitable fastening devices, such as the screws 11, with the flange 12 of the follower head 13.

10 14 designates a diaphragm constituting the movable member, the inner periphery of which is secured to the follower head 13 by means of suitable fastening devices 15 and a ring or washer 16, through which the fastening devices 15 pass. The outer periphery of the diaphragm 14 is held between the flange 17 located at the upper end of the casing 3 and the flange 18 located at the lower end of the upper casing 19, it being seen that 15 suitable fastening devices 20 are employed, which pass through the outer periphery of the diaphragm 14 and engage with the flanges 18 and 17, as will be readily apparent from the drawings. The follower head 13 20 is provided with a spider 21 which is connected with the boss 22, which latter carries a plate 23, between the outer periphery of which and the follower head 13 is located an outlet port 24, which is controlled by a valve 25, the latter being secured in place by means 25 of a washer 26 and a set screw or equivalent fastening device 27, which passes through said washer 26 and has engagement with the boss 22. The valve 25 is preferably disk 30 shaped and formed of a thin plate of metal, which is centrally supported so that the annular port 24 is suitably controlled at all times.

28 designates a partition member at the 40 lower portion of the casing 19, whereby a clearance space is formed between said member and the flexible diaphragm 14. The member 28 is provided with ports 30 there-through which are controlled by means of a 45 valve 31, preferably disk shaped and constructed in a similar manner to the valve 25, said valve 31 being secured in position by means of a disk or washer 32 and a fastening device 33, which engages one of the lugs 34 carried by the member 28.

35 designates a pan which is removably secured to the lugs 34 by means of suitable fastening devices, such as the screws 36 or their equivalents, it being noted that the diameter of the pan 35 is less than the diameter of the vacuum compartment in the casing 19. The upper end of the casing 19 is provided with an inwardly extending flange 37, which is suitably recessed at its upper end in order to receive a suitable gasket 38 of rubber, leather or other suitable material.

39 designates a collar which is provided with a flange 40 adapted to be seated on the upper end of the casing 19 and engage the

gasket 38 in order to form an air tight connection between these two members.

41 designates connections secured to the collar 39 and having their lower ends secured in any suitable manner to a dust pan 42 in which the dust, separated from the 70 dust laden air, is adapted to be received.

43 designates a bag of canvas or other suitable dust separating fabric which is adapted to be drawn over the dust pan 42 and the connections 41 and secured in place by any 75 suitable means.

44 designates a removable cover adapted to be seated on the flange 40 of the collar 39, it being noted that the cover 44 is suitably recessed as indicated at 45, thereby adapting 80 the same to receive the gasket 46 of rubber, leather or other desired material. The cover 44 has integral therewith in the present instance, an observation glass 47 which is provided with an air inlet 48, to which latter is 85 adapted to be connected the hose secured to the cleaning device, it being noted that the observation glass communicates with the chamber within the casing 19.

49 designates a plate to which is secured a 90 suitable handle 50, it being noted that said plate 49 rests on the top of the cover 44 and that rods 51 are provided which are pivotally supported at 52 to the casing 19, said rods 51 being adapted to pass through the 95 plate 49 and be secured in place by means of the nuts 53.

In the embodiment seen in Fig. 3 I have shown a construction in which the follower head or movable member of the pump is 100 shown as being a piston instead of a diaphragm, the only difference in such construction being that the inner end of the casing 19 is extended, as indicated at 54 in order to form a piston chamber 55, in which 105 the piston 56 is mounted, said piston being preferably rigidly connected with the connecting rods 9 by means of suitable fastening devices 57. The follower head 56 is suitably recessed at its periphery in order to 110 receive the packing 58, which is secured thereto by means of the ring 59 and suitable fastening devices 60. The follower head or piston 56 is provided with ports 61 there-through controlled by a valve 62 centrally supported by means of the fastening device 63 and the plate 64, as will be readily apparent to those skilled in this art, this valve 62 preferably corresponding to the construction 115 similar to the valves 25 and 31.

Since the construction of the other parts seen in Fig. 3 is similar to that already described in connection with Figs. 1 and 2, I have deemed it unnecessary to further describe the same.

The operation of my novel construction will now be readily understood and is as follows:—The motor is started, whereupon

the connecting rods 9 are reciprocated and thereby the diaphragm 14 or the piston 61. The diaphragm 14 is centrally apertured, as will be readily understood by reference to Fig. 1, so that the air is drawn through the inlet 48 into the observation glass 47, passing thence through the dust separating fabric 43, the dust and impurities contained in the dust laden air being separated from the air at this point, so that the air in its purified condition passes into the vacuum chamber within the casing 19 around the pan 35, through ports 30 into the chamber formed between the partition 28 and the diaphragm 14 and thence through the ports 24 into the pressure chamber 4 and thence through the discharge port 5 into the atmosphere. It will be readily apparent that in case it is desired to blow the dust from the articles, the 20 these will simply be connected with the outlet 5 and such operation can be readily accomplished.

In the present instance I have shown the connecting rods 9 as being rigidly connected with the follower head but it is of course to be understood that in some instances my device would still be operative if such connection instead of a rigid connection at this point, has a little flexibility.

I wish to call particular attention to the construction of diaphragm pump, in my present construction I employ a valve in the metal part of such pump the valve comprising a single piece of thin material. It will also be seen that the valve 31 is properly protected, owing to the pan 35 which is employed, so that there is no danger of any heavy particles of dust or dirt coming into contact with the valve mechanism, thereby reducing the efficiency of the apparatus.

When it is desired to remove the dust collector, it is simply necessary to remove the handle 50 after actuating the nuts 53 and removing the plate 49, whereupon the removable cover 44, together with the observation glass 47, can be readily removed. The collar 39 is then lifted out, together with the pan 42 connected therewith and the dust separating fabric 43 secured therearound. It will thus be apparent that in my present device the dust separating mechanism may be easily and quickly cleaned when desired and may be readily taken apart or assembled.

It has been found in practice that with a construction such as herein disclosed, a standard electric motor may be employed which may be run at a very high speed and the type of valves shown herein give very satisfactory results at high speeds.

The device is exceedingly compact and light and can be readily carried around by the handle 50 from one place to another

when desired, or it may be moved from place to place on its supporting rollers 2. In my present construction I employ an oscillating follower head or piston and the cylinder or its equivalent is made rigid while the connecting rod is preferably rigidly secured to the follower head or piston and the piston rod, as ordinarily used, is entirely dispensed with.

My novel vacuum producing apparatus is in practice made in two styles, the piston type with an oscillating piston and the diaphragm type with an oscillating follower head.

It will now be apparent that I have devised a novel and useful construction of a portable pneumatic cleaner, which embodies the features of advantage enumerated as desirable in the statement of invention and the foregoing description and while I have in the present instance shown and described a preferred embodiment thereof which gives in practice satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:

1. In a pneumatic cleaner, a casing having a pressure compartment and a vacuum compartment therein, a partition intermediate said compartments having ports therethrough, a valve for controlling said ports, a valve protector located above said ports, and vacuum producing mechanism located in said pressure compartment.

2. In a pneumatic cleaner, a casing having a pressure compartment and a vacuum compartment therein, a partition intermediate said compartments having ports therethrough, a valve for controlling said ports, a valve protector located above said ports, vacuum producing mechanism located in said pressure compartment, and a handle carried by said casing.

3. In a pneumatic cleaner, a sectional casing having superimposed vacuum and pressure compartments, a motor located in one of said compartments, connecting rods on opposite sides of said motor, a pump to which said connecting rods are secured, a partition in said vacuum compartment having valve controlled ports therethrough, and means in said vacuum compartment for deflecting the air passing to said ports.

JOHN W. SMITH.
